[57] CLAIM

The ornamental design for a mirror, as shown and described.

DESCRIPTION

FIG. 1 is a front left perspective view of a first embodiment of a mirror showing our new design;

FIG. 2 is a front elevational view thereof, the rear being plain and unadorned;

FIG. 3 is a side view thereof, the opposite side being a mirror image of the side shown;

FIG. 4 is an enlarged partial perspective view of the upper left hand corner of the mirror illustrating the decorative carving thereon;

FIG. 5 is an enlarged partial perspective view of the lower left hand corner of the mirror; and,

FIG. 6 is an enlarged partial front view of the upper central portion of the mirror illustrating the decorative carving thereon.
